UNITED STATES PATENT OFFICE.

GEORGE W. KORN, OF NEW YORK, N. Y.

DESIGN FOR A KNIFE-HANDLE.

SPECIFICATION forming part of Design No. 14,930, dated April 1, 1884.

Application filed October 25, 1883. Term of patent 7 years.

To all whom it may concern:

Be it known that I, GEORGE W. KORN, a citizen of the United States, residing in the city of New York, in the State of New York, have invented and produced a new and original Design for Knife-Handles, of which the following is the specification, reference being had to the accompanying drawings, forming part thereof.

10 Figure 1 is a plan view taken from the side. Fig. 2 is a plan view taken from the front of the handle.

15 The leading feature of my design consists in the handle having one end, *a*, square, or nearly so, the full depth of the handle as a base, the two edges starting from the ends of this base and slightly diverging until near the center of the

length of the handle, as at *b* and *c*, when the lines gently converge, until they approach each other, to a distance of about one-half the width 20 of the end whence they started. The other end of the handle has a dish-shaped ledge, *d*, within which is semicircle projection *e*, with radiating cords from its center, thus presenting to the eye a novel and unique design for a 25 knife-handle.

I claim—

The design for a knife-handle, having the shape and configuration shown and described.

GEORGE W. KORN.
